UNITED STATES PATENT OFFICE.

WILLIAM H. McCausland, OF LOS ANGELES, CALIFORNIA.

METHOD OF ATTACHING HALF-SOLES TO THE BASE OF OLD SHOES.

1,211,326.

Specification of Letters Patent.

Patented Jan. 2, 1917.

Application filed May 31, 1916. Serial No. 100,887.

To all whom it may concern:

Be it known that I, WILLIAM H. McCausland, a citizen of Great Britain, residing at Los Angeles, in the county of Los Angeles and State of California, have invented new and useful Improvements in Methods of Attaching Half-Soles to the Bases of Old Shoes, of which the following is a specification.

10 This invention relates to a method of attaching half-soles to worn shoes, by which shoes known as hand sewed Goodyear welt, or any other shoe, the out soles of which are attached to a welt, this welt being sewed to 15 the insole by a separate seam generally known as inseam, may be half-soled or retapped without distorting the shape or destroying the smoothness of the insole.

The method hitherto in use has always 20 been to remove the worn part of the sole to skive or bevel the end of the old sole, to lay the half sole or tap on the bevel and nail it through the insole. The nails being driven through the outsole where the two beveled 25 edges overlap passing through the insole and clenching against an iron last inside the shoe. The sole was then ready to sew to the welt. This nailing always distorts the shape of the insole and partially destroys the smoothness and flexibility for which the shoes 30 above referred to are noted.

My novel method removes the old or worn part of the sole in the same manner as the old methods, but instead of nailing the half- 35 sole or tap through the insole, to attach it to the shank of the old sole either by cementing, sewing or other attachment entirely separate and independent of the insole.

It is an object of this invention to provide 40 a method for attaching outer half-soles to the shank portion of the outer sole of a shoe which will be more durable and secure than those attached by the methods in common practice.

45 Another object is to provide a method for applying half-soles to worn shoes which shoes will be perfect on the inside, and will not be distorted out of shape.

Another object is to provide a method for 50 applying half-soles to the bases of old shoes whereby the same will retain their original flexibility. The shoes half-soled by my new method have no nails to extend through the insole, and consequently roughness of the 55 insole, or discoloring of the hose by rusty nails is entirely avoided.

Other objects will appear hereinafter.

The invention is illustrated in the accompanying drawings in which:

Figure 1 is a view in perspective showing 60 a half-sole applied to a worn shoe by my improved method. Fig. 2 is a view in side elevation of the shoe in a condition for the application of the half-sole which is here illustrated as adjacent the shoe ready to be 65 attached thereto. Fig. 3 is a fragmentary view illustrating the manner in which the half-sole is secured to the shank of the outer sole.

Referring to the drawings, 5 indicates a 70 shoe having an upper 6, an insole 7, and a shank portion 8 of an outer sole. The main portion of the outer sole has been cut away, as indicated in Figs. 2 and 3, and the shank portion alone remains. The shank portion 75 has been prepared after the removal of the remainder of the outer sole with a beveled edge 9 which extends laterally and the width of the outer sole. For a purpose which will hereafter be set forth, the shank portion has 80 been loosened from the insole and the welt by cutting the stitch along the marginal edges of the sole so that the shank may lie in the position shown in Figs. 2 and 3.

A half-sole 10 is provided for the shoe 85 and shaped in a manner to substantially conform to the last of the old shoe and has its edge 11 formed in a beveled manner with an angle complementary to the angle of the bevel formed on the edge of the shank portion 90 of the shoe, as indicated by the numeral 9. When the shoe and the new half-sole have been prepared in the manner described they are in condition to be stitched, or otherwise fastened together.

The first step in the operation of applying the sole is to treat the adjacent beveled faces of the ends 9 and 11 of the shank and half-sole, respectively, with a cement or other suitable water-proof adhesive. Next, 100 the shank portion is bent outwardly and a stitch 12 is made across the shank and sole and through the overlapping beveled edges thereof. The half-sole is then drawn in to position over the insole and is pegged thereupon in a manner to hold it during the stitching operation. When the sole is so pegged, a stitch 14 is made around the entire marginal edge of the shoe and through the welt, and continued along the shank portion 110 of the outer sole to re-stitch the shank along the portion which was removed to allow

the shank to be stitched along the stitching 12 as previously described, after stitching the marginal edge to the welt the peg holding the sole in place may be removed.

5 It will thus be seen that I have provided a simple method for securing a half-sole to the welt and the shank of a shoe with a stitch and without the use of nails or metallic fasteners.

10 I claim:

A method of half-soling shoes with leather soles, consisting in cutting away the worn sole, beveling the transverse edge of the shank portion of the outer sole at a point 15 adjacent the terminating line of the instep and loosening said shank portion from the insole and the welt of the shoe by cutting

the stitches along the marginal edges of the sole, applying an adhesive to the beveled face of said shank portion, preparing a 20 leather half-sole with a beveled edge complementary to that of the shank portion, and placing the same on the beveled edge thereof, stitching the overlapping beveled edges of the shank portion and the half-sole 25 together, and finally stitching the half-sole to the welt of the shoe along its remaining marginal edge, whereby the insole of the shoe remains free from any nails or tacks driven therethrough.

In testimony whereof I have signed my name to this specification.

WILLIAM H. McCausland.
